UNITED STATES PATENT OFFICE.

WILLIAM GEORGE CHRYST, OF PHILADELPHIA, PENNSYLVANIA.

SCREEN INCLOSURE.

Application filed February 3, 1926. Serial No. 85,645.

This invention relates to screen inclosures especially adapted for use in financial institutions, such as banks.

The screens now in use have a desk counter built integrally therewith. This is objectionable because when it is desired to re-arrange the procedure in clerical work, the desk counter cannot be moved to suit the re-arrangement. Consequently many parts of the desk counter idly occupy valuable space. Furthermore, with the old type of screen, a person transacting business at a screen window is in full view of persons waiting in line. This is not only embarrassing but dangerous as it may entice one to rob.

Another objection to the old screen is that a person carrying a package, as a lady with her handbag, often requires the use of both hands at the window, and, having no place to lay the package, uses but one hand and thereby causes delay.

A further objection is that the clerk behind the screen, especially in close places, becomes fatigued and drowsy. This is due principally to poor ventilation and an insufficient supply of fresh air to the respiratory organs. Furthermore, with the old type of screens no protection is afforded to the clerks against the danger of being shot by intruders.

The objects of my invention are to provide a screen inclosure which will be free of the above objections and which may be made of a neat and attractive design.

These objects, and other advantageous ends which will be described hereinafter, I attain in the following manner, reference being had to the accompanying drawings in which:

Figure 1 is a fragmentary front elevation of a screen made in accordance with my invention;

Figure 2 a section on line 2-2 of Figure 1;

Figure 3 a rear elevation of the screen shown in Figure 1;

Figure 4 a section on line 4-4 of Figure 3;

Figure 5 a section on line 5-5 of Figure 3;

Figure 6 an enlarged fragmentary section on line 6-6 of Figure 1; and

Figure 7 an enlarged fragmentary section on line 7-7 of Figure 3, showing the lock in full.

Referring to the drawings, 1 indicates a

base built up of superposed blocks 2, a wall facing 3, preferably marble, secured to the outer side of the blocks, and a facing 4, preferably of plaster, secured to the inner side of the blocks. A shelf 5 is secured on the top of the base and preferably extends a short distance beyond the wall facing 3. An upright wall 6 of bullet proof material is mounted on the shelf near its inner edge and has perforated portions 7 preferably made of strong woven wire of fine mesh 8 secured to the wall by suitable frames 9. This woven wire is of such strength and mesh that a bullet will not pass through it. A superstructure supporting member 11 is mounted on the upper edge of wall 6 and on spaced columns 10. This member is preferably in the form of an inverted channel having perforations 12 so that fresh air may pass from outside to inside the inclosure and thus ventilate the space within the inclosure. A superstructure 13 is suitably secured on channel 11 in front of perforations 12. The superstructure consists of a series of windows 14 arranged to meet above each column 10 and a cornice 15 detachably secured to the windows in any suitable manner. This arrangement allows the cornice to be made at the factory and avoids considerable labor expense in properly fitting the cornice to the windows as is usual with the old types of built-in cornices. Each window may comprise a frame 16 of channel cross section and moldings 17 secured within the frame for holding a glass pane 18 in position.

A screen window 19 in wall 6, has a shield 20 at each side extending outwardly from the wall. These shields obstruct the view of the window to the people waiting in line, and prevent the embarrassment resulting from others seeing what business is transacted by the person at the window.

A wicket 21 slidable in guideways 22 on the opposed sides of shields 20, may be held in any raised position by a lock 23. This lock is secured to channel 11 and has a spring-pressed plunger 24 which may engage within a selected hole 25 in the wicket to hold it in position at different heights. When the wicket is lowered from a raised position, a handle 26 is pulled to withdraw plunger 24 from the hole 25 and turned to the left to bring a pin 27, extending from the plunger, against a shoulder 28 on the lock casing to hold the plunger in withdrawn position. As the wicket is slid downward

to its lowermost position a tripping member 29 on the wicket engages pin 27 and moves it from engagement with shoulder 28 to free the plunger 24 to the action of its spring which will slide it into the uppermost hole 25 on the wicket. The wicket is thus automatically locked when brought to its lowermost position.

For posting notices or for advertising purposes, I preferably provide a recess 30 in shelf 5 and slidably mount a plate member 31 in a pair of channels 32 secured at the sides of the recess, and then cover this recess by resting a glass plate 33 on the channels so that it is flush with the shelf. A card 34 or other matter may be placed on member 31 and moved under glass plate 33 where it may be readily seen by persons at the window as shown in Figure 2.

20 The desk counter consists of a number of tables 35 which may be moved about and placed in any desired position to suit any system for progress in clerical work.

25 To facilitate the handling of currency, I preferably provide a box 36 which has a drawer 37 held within the box by a spring-pressed latch 38 held in locked position by a lid 39 hinged at 40 and locked to the casing at 41 by a suitable combination lock. The box may be provided with a partition 42 and the drawer and partition may be provided with suitable compartments for keeping various papers or articles in order.

30 The screen inclosure above described affords shelf room on which packages or other articles may be placed while transacting business; obstructs the view of what takes place at the window to persons other than the person at the window; allows the fresh air to pass from outside to inside the screen through the perforations 12 and thus ventilate the inclosure; affords protection, to the clerks behind the screen, by the bullet-proof wall 6; and allows the desk counter to be arranged to suit any system of work.

35 While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

40 Having thus described my invention, what I claim as new and desire to secure by Letters Patent is:—

1. A screen inclosure including a base; a shelf on the base; an upright wall on the shelf; columns on the shelf spaced from the wall; an inverted channel having air ports and resting on the wall and the columns, and a superstructure secured to the channel.

2. A screen inclosure including a base; a shelf on the base; a wall extending upwardly from near the inner edge of the shelf; columns on the shelf spaced from the wall; a perforated supporting member resting on the columns and the wall with the perforations between the columns and the wall, and a superstructure secured to the supporting member in front of the perforations.

3. A screen inclosure including a base having an inside wall and an outside wall, a shelf on the base reposited with its inner edge close to the inside wall, its other edge extending to a greater degree beyond the outside wall, an upright partition on the shelf having a plurality of screened openings and a wicket opening, said partition being positioned on the shelf adjacent its inner edge, a series of columns on the shelf spaced from the wall and stationed between series of said screened openings as desired, an inverted channel mounted on said columns and partition having perforations for allowing air in front of said partition to circulate through said channel, a superstructure on said channel positioned so that said perforations are located between the rear of the superstructure and the front of the partition, said superstructure having channeled openings terminating substantially in line with said columns and adapted to be glazed, and an ornamental cornice integral with said superstructure.

4. A screen inclosure comprising a base, a shelf on the base, an upright partition on the shelf having a plurality of openings adapted to be protected by bullet-proof screens, said partition being disposed on said shelf near the inner edge thereof, columns on said shelf stationed between said partition and the outer edge of the shelf, a superstructure mounted on means positioned on said partition and columns and including glazed openings and an ornamental top, and air ports in said means located in the portion thereof between said partition and superstructure.

5. A screen for bank inclosures including a base, a shelf on said base, an upright partition having openings adapted to be protected by bullet-proof devices and a wicket adapted to be opened or secured in a desired position, guarding means on said shelf positioned so that observation through said wicket may be carried on only from a position substantially in front thereof, a superstructure positioned above and to one side of said partition, and means, having ports for the circulation of air therethrough, connecting said partition and superstructure.

In testimony whereof I have signed my name to this specification.

WILLIAM GEORGE CHRYST.
